A. G. Schumann.

Attorney
John Schumann, Jr.

UNITED STATES PATENT OFFICE.

ALFRED G. SCHUMANN, OF BALTIMORE, MARYLAND.

OIL OR GAS BURNER.

1,425,343.

Specification of Letters Patent.

Patented Aug. 8, 1922.

Application filed April 14, 1921. Serial No. 461,299.

To all whom it may concern:

Be it known that I, ALFRED G. SCHUMANN, a citizen of the United States, residing at Baltimore, in the State of Maryland, have 5 invented certain new and useful Improvements in Oil or Gas Burners; and I do hereby declare the following to be a full, clear, and exact description of the invention, such as will enable others skilled in the art to 10 which it appertains to make and use the same.

This invention relates to improvements in gas and oil burners, and one of its objects is the provision of a novel device of this 15 kind which shall be especially adapted for use in connection with open hearth and other metallurgical furnaces, in connection with which a wide variety of fuels, such as coke-oven gas, producer gas, oil, tar and the like, 20 may be used, and in connection with which heated air under pressure or super-heated steam may be employed to atomize and spray the fuel.

Another object of the invention is the provision of a burner of the kind stated which 25 shall be adapted to so thoroughly atomize the fuel and mix it with the atomizing and spraying agent as to permit the production of the maximum heat from a given quantity 30 of fuel.

Another object of the invention is the provision of a burner of the kind stated which shall be provided at its tip with a plurality of fuel discharge ports from which will 35 issue jets of combustible vapor uniting at a distance from the burner to produce a long column of flame the tip of which will impinge against and extend over the entire surface of the metal being treated, whereby 40 to enable a better quality of steel to be produced in a shorter time than has heretofore been possible.

A further object of the invention is the provision of a burner of the kind stated 45 wherein the fuel discharge ports shall be of various depths whereby to produce jets of combustible vapor of various lengths, the jets uniting at a distance from the burner to produce a column of flame having a tip 50 which will impinge against the metal being treated at points in close proximity to the burner as well as points remote therefrom and produce a uniform temperature of high degree throughout the entire length and 55 breadth of the furnace.

A still further object of the invention is

the provision of a burner of the kind stated wherein the jets of vaporized fuel issuing from the fuel discharge ports may be easily and quickly controlled whereby to permit 60 the delivery of the combustible vapor at any desired distance from the burner into the furnace.

With the above and other objects in view, the burner consists in the construction, combination and arrangement of parts hereinafter fully described and claimed, and illustrated in the accompanying drawings, wherein:

Figure 1 is a view in longitudinal section 70 of a burner constructed in accordance with my invention.

Figure 2 is a sectional view of the front end of the burner on an enlarged scale.

Figure 3 is a sectional view taken on the 75 plane indicated by the line 3—3 of Figure 1, looking in the direction indicated by the arrows.

Figure 4 is a view in end elevation of the tip of the burner.

Figure 5 is a sectional view taken on the plane indicated by the line 5—5 of Figure 2, looking in the direction indicated by the arrows.

Figure 6 is a detail plan view illustrating 85 the formation of one of the vaporizing, mixing and discharge ports of the burner.

Figure 7 is a view in end elevation of the tip of a slightly modified form of the burner, and

Figure 8 is a view similar to Figure 2 illustrating a further modified form of the burner.

Referring to the drawings by reference characters, 1 designates a casing through 95 which the super-heated steam or heated air under pressure is forced. The steam or air is supplied to the casing 1 by a pipe 2 leading from any suitable source of supply and connected to the casing by a coupling 3. A 100 tube 4, which is smaller in diameter than the casing 1 and through which the fuel is forced, is arranged within the casing in spaced relation thereto. The fuel, which may be coke-oven gas, producer gas, tar or 105 oil, is fed under pressure to the tube 4 through a pipe 5 which leads from any suitable source of supply and which is equipped with a controlling valve 6. The fuel supply pipe 5 is connected to the coupling 3 by a 110 nipple 7. The rear end of the tube 4 is reduced as at 8, and such end passes through

the nipple 7 to establish communication between the pipe 5 and tube 4. Metallic packing 9 and a packing gland 10 are provided for the purpose of establishing a liquid pipe connection between the nipple 7 and the reduced end 8 of the tube 4. The tube 4 extends through the casing 1 to a point adjacent the forward end or tip thereof. The forward end of the tube 4 is reduced as at 11 and has removably connected therewith a nozzle 12.

The nozzle 12 is substantially cylindrical in formation, it has a longitudinally extending bore 13, and its forward end is fully closed. It is threaded as at 14 to permit it to be removably connected to the tube 4. The nozzle 12 is supported in spaced relation to the casing 1 by rear ribs 15 and front ribs 16 which have a close fit with the inner wall 20 of the casing. The rear ribs 15 are merely spacing ribs, while the front ribs 16 in addition to being spacing ribs provide together with the casing 1 a plurality of ports 17 in which the fuel is atomized and mixed 25 with the steam or air, and from which the resultant mixture passes in jets of combustible vapor. Apertures 18, extending radially through the nozzle 12, establish communication between the bore 13 and the ports 17. The apertures 18 are located centrally between the ends of the ports 17.

The ports 17 have intermediate restricted portions 19 which are in length and width slightly greater than the diameter of the apertures 18 and within the planes of which the apertures are located. The ports 17 gradually decrease in width from their rear ends in the direction of the restricted portions 19 and gradually increase in width for 40 the restricted portions in the direction of the tip of the burner, as clearly illustrated in Figure 6.

As illustrated in the drawings, the nozzle 12 is located wholly within the casing 1. The position of the front end of the nozzle 12 with respect to the front end or tip of the casing 1 may be varied by adjusting the nozzle on the tube 4 or by adjusting the tube 4 with respect to the casing.

From the foregoing, it should be apparent that the fuel is thoroughly atomized and mixed with the air or steam before it is discharged from the tip of the burner. It should be further apparent that, since the tip of the burner is provided with a plurality of ports 17 jets of highly combustible vapor will issue from the tip of the burner, and that the jets of highly combustible vapor will unite at a distance from the burner and produce a long column of flame having a tip of wide area and of uniform temperature throughout its entire area. As the jets of combustible vapor issue from the ports 17 at high velocity, and as the resultant 60 flame has a tip of wide area and of uniform

temperature throughout its entire area, the flame will impinge against the entire surface of and uniformly heat the metal being treated, resulting in the production of a high grade steel in a shorter time than has heretofore been possible.

It should also be apparent that, since the fuel is atomized in separate ports when the steam or air is at its highest velocity, and since the atomized fuel and the air or steam expand immediately after the atomization of the fuel, the atomization of the fuel and its mixture with the air or steam is so thorough that heavy fuel such as tar, crude oil and the like may be effectively used. It 75 should also be apparent that the burner has a capacity for using lighter fuel such as coke-oven gas, producer gas and the like.

The length and intensity of the flame may be regulated by controlling the admission 85 of air or steam to the casing 1 and fuel to the tube 4. The steam or air during its passage through the casing 1 travels about and along the tube 4 and as a consequence the fuel is heated to a high degree before it 90 issues from the apertures 18 into the ports 17.

In order to permit of the production of fuel jets of various lengths so that the resulting flame will impinge against the metal 95 being treated at points in close proximity to the burner as well as points remote therefrom with an equal heat intensity at all points, the fuel discharge ports are, as shown in Figure 7, made of various depths. The 100 fuel discharge ports in this figure are designated 17^a, and by reference to this figure it will be seen that the two lowermost ports are the shallowest and that the ports gradually increase in depth in opposite directions 105 from the lowermost ports.

In Figure 8 a further modification of the burner is shown. This burner differs from the burner shown in Figures 1 to 6 inclusive only in that the casing 1 is provided 110 with a flaring tip 1^a and that the front end of the burner 13 is located within and is similar in formation to the flaring tip.

When burning coke-oven gas or producer 115 gas, air under pressure is employed as the atomizing and spraying medium, and when using this fuel and atomizing and spraying medium means are provided by which the casing 1, the tube 4, and the nozzle 13 may be water cooled.

From the foregoing description, taken in connection with the accompanying drawings, it should be apparent that the burner is simple, durable and effective, that it may be manufactured and sold at a comparatively low cost, that it has capacity for the use of a wide variety of fuels, and that the flame produced has a wide tip of uniform temperature throughout its entire area. It should be further apparent that the burner 125 130

is especially adapted for use in connection with open hearth and other metallurgical furnaces. It may be effectively used in connection with steam boiler furnaces of all kinds.

Having thus described the invention, what I claim is:—

1. A burner of the character specified comprising a nozzle having a central bore closed at its outer end, and having longitudinal ports exterior to the central bore constricted intermediate their ends, and having openings connecting the bore with the constricted portions of the ports.

15 2. A burner of the character specified comprising a nozzle having a central bore closed at its outer end, and having longitudinal ports exterior to the central bore with their opposite end portions outwardly 20 flared, and having openings connecting the bore with the ports intermediate their flared ends.

3. An oil or gas burner including a nozzle having a plurality of longitudinally extending discharge ports provided with restricted central portions and outwardly flaring front and rear portions, and said nozzle having apertures establishing communication between the interior thereof and the 30 restricted portions of the ports.

4. An oil or gas burner including a nozzle

having a plurality of discharge ports of various depths, and the nozzle having apertures establishing communication between the interior thereof and the ports.

35

5. An oil or gas burner including a nozzle having a plurality of discharge ports of various depths provided with restricted portions, and the nozzle having apertures establishing communication between the interior thereof and the restricted portions of the ports.

40

6. An oil or gas burner comprising a casing, a fuel supply pipe located within and spaced from the casing, a nozzle located within the casing and having its front end closed and communicating at its rear end with the fuel supply pipe, and relatively spaced front and rear ribs carried by the nozzle and engaging the inner wall of the 45 casing to support the nozzle in spaced relation to the casing and to provide the nozzle with a plurality of discharge ports, and the nozzle having apertures establishing communication between the interior thereof and the discharge ports.

50

In testimony whereof I affix my signature in presence of two witnesses.

ALFRED G. SCHUMANN.
